RADIO TRANSMITTING AND RECEIVING
SYSTEM

Irving Wolff, Merchantville, N. J., assignor, by
mesne assignments, to Radio Corporation of
America, New York, N. Y., a corporation of
Delaware

Application November 30, 1934, Serial No. 755,286

8 Claims. (Cl. 250—33)

This invention relates to radio transmitting and receiving systems, and more particularly to a device of this character in combination with adjustable means for simultaneously varying the exposed dimensions of an antenna in order to maintain constant its directional radiation characteristic.

An object of my invention is to provide a construction of high frequency antenna apparatus having means for accurately adjusting different sections thereof for maintaining optimum radiating characteristics.

Another object of my invention is to combine in apparatus of the character above suggested an antenna length control with control of a tuning device.

Another object of my invention is to provide an antenna system having telescopically disposed radiating sections and telescopically disposed non-radiating sections, all of which may be simultaneously adjusted from a uni-control device.

When an antenna system is used for long wave radio transmission or reception at a series of different wave lengths, good results can be obtained by re-tuning the electrical circuits of the associated radio apparatus to give the desired response at each frequency. When working with short waves, however, the antenna may be of the same order of magnitude as, or longer than, the length of the wave being radiated or received. It then becomes necessary to re-proportion the exposed surfaces of the antenna with respect to the radiated wave, in addition to re-tuning the electrical circuits of the radio apparatus. Failure to provide suitable adjustment of the antenna system itself involves serious energy losses. Furthermore, the desired directional characteristic cannot be satisfactorily maintained for efficient transmission and reception between two geographically spaced antennae unless some means are provided for variably exposing different portions of each antenna according to the operating wave length.

In carrying out my invention I prefer to arrange the various movable elements of the antenna system in such manner that their effective radiating length may be adjusted to any desired wave length for securing high operating efficiency of the radio communication system of which the antenna forms a part.

The foregoing objects and advantages of my invention will best be understood upon reference to the following detailed description when

read in connection with the accompanying drawings, in which—

Figure 1 shows in sectionalized elevation a view of one embodiment,

Fig. 2 shows on a more reduced scale a fragmentary view in elevation of the same embodiment when the telescoping sections thereof are fully extended,

Fig. 3 illustrates diagrammatically the current distribution on my antenna system when properly adjusted to radiate or to receive radio waves of a given wave length,

Fig. 4 illustrates diagrammatically the corresponding current distribution on an antenna system improperly adjusted, and

Fig. 5 shows diagrammatically how the directional response or radiating characteristic of a vertically disposed antenna system varies with different wave lengths.

My antenna system may be used either for radio transmission or reception. In either case, the antenna length should be some definite multiple of half the wave length. It is desirable, therefore, to provide variable means for adjusting the apparatus so as to provide efficient transmission or reception at different frequencies. For making such adjustments it is again desirable that a uni-control device be provided in which both the antenna length and whatever tuning adjustment there may be incorporated in the radio apparatus shall be simultaneously adjusted to a desired frequency response.

In the transmission and reception of ultra-short waves, it is of the utmost importance that the minutest details of the radiating characteristics of an antenna system should be considered and adjusted to optimum operating conditions. Thus, if it is desired that the antenna arms be made to include three half-wave radiating sections, then these radiating sections should, by preference, be interconnected by non-radiating half-wave sections in order that a satisfactory wave front may be obtained in the radiating characteristic.

To illustrate this point I have shown in Fig. 3 an antenna system which is composed of three radiating sections 5, 6 and 7, respectively, and two non-radiating sections 8 and 9. If each of these sections is adjusted to a wave length—

$\frac{\lambda}{2}$

then it will be seen that the current distribution is as indicated by the half-wave loops a, b and c. The loop b has the same phase as the two loops a

55

and c because the non-radiating half-wave sections 8 and 9 are interposed. If, on the other hand, a different frequency were to be impressed upon the antenna system and one to which it is not properly adjusted, the results obtained might be as shown in Fig. 4 where the antenna length is indicated as—

$$\frac{4\lambda}{2}$$

10 The inefficiency of the system under these conditions becomes apparent when it is considered that the current distribution becomes broken up with phase reversals, as shown by the curves a', b' and c'. In this case the radiating sections 5' 6' and 15' are not of suitable length to impress half-wave length radiations symmetrically thereupon. Each section is, in fact, too short to comprehend a full half-wave. Furthermore, the non-radiating sections 8' and 9' are not of suitable length for 20 transposing the phase in the desired manner, as shown in Fig. 3. The maximum radiating effect, instead of being perpendicular to the antenna axis, becomes tilted at an undesirable angle. In the example given the angle $\theta=62^\circ$, approximately.

It is, therefore, for the purpose of avoiding such adverse conditions that I provide suitable adjustments in my antenna system so that both the radiating sections and the non-radiating sections 30 may be varied in electrical length simultaneously.

Referring now to Fig. 1, I show an antenna system suitable for radiating or receiving radio waves. A pair of stationary tubular members 11 is provided. These are mounted upon insulating supports 13. The insulators 13 are preferably carried on a centrally disposed framework 12 which serves also to support the various moving elements comprised in the uni-control device, as well as a tuning condenser 14. The latter is 35 shown merely for the purpose of illustrating how my uni-control device may be operated to simultaneously adjust both the antenna length and the resonant conditions of a radio network. The stationary sections 11 are arranged to cooperate 40 with telescoping sections 15. The sections 11 and 15 may be considerably elongated or telescoped one within another so that the effective electrical length shall be—

$$\frac{\lambda}{4}$$

50 on each side of the center of symmetry of the antenna system. Thus, if energy is applied to these sections through the leads 16, a half-wave length will be radiated from between the outer extremities of the two sections 15.

In order to obtain the necessary adjustment, each of the telescoping members 15 is provided internally with a nut 17 threaded to mesh each with a screw-threaded shaft 18, the turning of 60 which may be effected by means of a crank 19 mounted on a shaft 20, which shaft carries a bevel pinion 21 meshing with a bevel gear 22, the latter being mounted on an insulating member 23 into which the ends of the threaded shaft 18 are key-65 socketed.

The structural elements thus far described may be seen to be made suitably adjustable for producing a half-wave length of radiation on the 70 fixed sections 11 in cooperation with the adjustable sections 15. Further radiating sections each having an effective radiating length of—

$$\frac{\lambda}{2}$$

75 are provided by the telescoping members 24 and

25. Each of the members 24 is secured to one or the other of the members 15, respectively. The mechanical juncture is in the form of an insulating member 26. A pair of insulators 36 have each a clearance hole therein for permitting the members 24 to slide up and down therein without danger of misalignment. The insulators 36 are mounted on any suitable support, as shown.

The telescoping members 25 are held in position telescoped within the members 24 and adjustably elongated by means of nuts 27 which mesh with the threaded shafts 18. Studs 37 are inserted through slots 38 and secured each to one of the telescoping members 25 to prevent the same from turning on its axis. The pitch of the thread along the portion of the shaft 18 over which the nut 27 is movable is made approximately three times as great as the pitch of the thread over which the nut 17 is movable. Thus, the telescoping members 25 will be caused to be extended 20 outwardly from and with respect to the members 24 approximately twice as fast as the outward extension of the member 15 with respect to the stationary members 11. The elongation of the sections 25 and 24, taken together, is made twice as 25 great as the elongation of the sections 15 and 11, taken together, because in the first instance a half-wave length is required and in the second instance only a quarter-wave length is required.

For the purpose of reversing the phase relation 30 between the outer extremity of the member 15 with respect to the inner extremity of the member 24 I provide a loop having approximately an electrical wave length of—

$$\frac{\lambda}{2}$$

This loop consists of two straight tubular sections 28 and 29, each being adjustably telescoped within the straight portions of a U-shaped tubular member 30. The section 28 is mounted off 40 the outer end of the radiating section 15, the connection thereto being made by means of a conductive member 31. Likewise, the section 29 is connected to the radiating section 24 by means 45 of a conductive member 32. The electrical length of the circuit including the members 31, 28, 30, 29 and 32 may be simultaneously adjusted to

$$\frac{\lambda}{2}$$

50

while any desired adjustment is correspondingly made with respect to the radiating sections. This U-shaped link is to be considered as non-radiating because, although each portion thereof is in itself a radiator, its overall effect is substantially nullified by the parallelism between respective portions.

To compensate for the condition in which the connecting links 31 and 32 would unduly increase the effective length of the non-radiating loop, this 60 loop in its entirety may be adjustably shortened by controlling the position of the U-shaped member 30 along with the adjustment of the length of the radiating sections. This is preferably accomplished by means of a threaded rod 33 of insulating material which engages with threaded portions of the U-shaped member 30. The turning of the threaded rod 33 may be accomplished by means of a driven gear 34 meshing with a pinion 35 which is either mounted on or made 65 integral with the insulating member 23. The pitch of the thread on the shaft 33, as well as the gear ratio between the members 34 and 35, is suitably determined for obtaining an effective 70 electrical length equal to a half-wave length on 75

the non-radiating sections for any desired adjustment of the effective electrical length of the radiating sections.

In order to carry out the scheme as represented in Fig. 3, both radiating and non-radiating sections, as shown above the center of Fig. 1 are duplicated below the center line. A symmetry of parts may thus be obtained for any desired adjustment. Also, for any desired adjustment 10 the centrally disposed quarter-wave length sections may be caused to cooperate to produce in effect a single radiating section having a value of—

$$15 \quad \frac{\lambda}{2}$$

whereas each of the outer telescoping sections above and below the mid-sections may be adjusted to a value of

$$20 \quad \frac{\lambda}{2}$$

and each of the non-radiating sections is also simultaneously adjustable to a value of—

$$25 \quad \frac{\lambda}{2}$$

In Fig. 1 the telescoping sections have been shown in a fragmentary manner in order to give a better idea of the working parts, whereas in Fig. 2 the relationship between diameters and length of the various sections is, perhaps, a trifle better proportioned to exemplify the considerable length of the antenna system compared with its diameter. Also, in Fig. 2, the telescoping sections have been shown fully elongated. In other respects there is no difference in the showing of the two figures.

Fig. 5 shows diagrammatically how the directional characteristic of an antenna system such as mine varies with different operating wave lengths. The curve λ has been plotted against different angles θ representing the axis of radiation with respect to the axis of the antenna system. The peak of energy radiation intensity is indicated as having a value of unity in a horizontal direction when the antenna axis is vertical. For such an antenna the directional pattern loses efficiency very rapidly and has substantially a zero value at an angle θ of approximately 70° . Between the values $\theta=70^\circ$ and $\theta=48^\circ$ a phase reversal of energy takes place. Thence the curve of intensity rises slightly and then descends again to a zero value for projection of radio waves in a vertical direction, or where θ equals 0° .

Without changing the antenna length, but upon impressing thereon a wave having a value 1.25λ , the directional characteristic becomes altered according to the broken line indicated in the diagram. The peak intensity occurs in a direction where $\theta=62^\circ$. Since the efficiency of wave propagation in a horizontal direction is the object generally sought, and since the efficiency in the case last illustrated by the broken line 1.25λ is almost nil in a horizontal direction, it may readily be seen why it is so essential to adjust the antenna length so that each section shall have a value of approximately—

$$70 \quad \frac{\lambda}{2}$$

In place of an antenna system having only three sections of a half-wave length each, it may be desired to employ any of the well known types of directional antenna and to provide 75 therefor means for maintaining constant its di-

rectional characteristic at different frequencies.

Although I have disclosed herein certain specific means for accomplishing the objects of my invention, these are given merely by way of example and are not to be construed as limitations to the scope of my invention. Other modifications will suggest themselves to those skilled in the art. My invention, therefore, is to be considered as having as broad a scope as is permitted by the prior art and by the spirit of the appended claims.

I claim as my invention:

1. A radio system comprising an antenna, a resonant circuit, means for adjusting the dimensions of said antenna so that its effective length is substantially equal to an odd multiple greater than one of half wave lengths of the energy to be impressed thereon, means for reversing the phase between adjacent oppositely phased half wave antenna sections, means for adjustably tuning said resonant circuit, and a uni-control device operably connected to said antenna adjusting means, to said phase reversing means and to said tuning means for maintaining suitable coordination of the respective adjustments thereof.

2. A system in accordance with claim 1 characterized in that said antenna is directional and means are provided in operable connection with said uni-control device for so adjusting the dimensions of the antenna as to maintain the directional pattern thereof substantially constant at different frequencies.

3. In a system combining an antenna device with radio apparatus, means for adjusting the effective antenna dimensions to a half-wave length of the radio energy and for adjusting the same to a multiple of said half wave length, means for reversing the phase between adjacent oppositely phased half wave antenna lengths, means for tuning said apparatus in accordance with the wave length of the energy impressed on said antenna, and a uni-control device operatively connected to the first and second mentioned means for simultaneously varying the same in a mutually coordinated manner.

4. The combination as set forth in claim 3 characterized in that said antenna device is directional and means are provided in operable connection with said uni-control device for so adjusting the dimensions of the antenna as to maintain the directional pattern thereof substantially constant at different frequencies.

5. In a device of the class described, an antenna, a radio-frequency tuning device, means for adjusting the dimensions of said antenna in proportion to one half of an odd multiple greater than one of the wave length of a predetermined radio signal impressed upon said antenna, a phase-shifting section of antenna serially included between adjacent oppositely phased half wave antenna lengths, means for adjusting said tuning device to said wave length, means for maintaining the directional pattern of said antenna substantially constant at different frequencies, and a uni-control device operatively connected to the first mentioned means and to the said phase-shifting section for adjusting the same simultaneously.

6. A device in accordance with claim 5 characterized in that said antenna is directional and means are provided in operable connection with said uni-control device for maintaining the directional pattern of said antenna substantially constant at different frequencies.

7. In an antenna system, a plurality of sections telescopically adjustable to add multiples of a half wave length, a plurality of phase-shifting sections interconnecting certain of the first 5 said sections, means for so adjusting the exposed dimensions of the first of said sections and the second mentioned sections as to maintain a uniform directional radiation characteristic at different wave lengths, and uni-control means for 10 effecting said adjustments simultaneously.

8. In an antenna system, a plurality of tele-

scopically disposed tubular radiating sections of which an outer section and the exposed portion of an inner section constitute a half-wave-length radiator, a plurality of phase reversing sections interconnecting different sets of half-wave-length radiators, and means for simultaneously adjusting the effective lengths both of radiators and of the phase reversing sections to obtain an optimum directional characteristic for a given wave length of energy impressed upon said system. 10

IRVING WOLFF.
